UNITED STATES PATENT OFFICE.

EDWARD M. HEYLMAN, OF SOUTH BEND, INDIANA, ASSIGNOR TO OLIVER CHILLED PLOW WORKS, OF SOUTH BEND, INDIANA.

PLOW.

1,386,866.

Specification of Letters Patent.

Patented Aug. 9, 1921.

Application filed March 29, 1918. Serial No. 225,517.

To all whom it may concern:

Be it known that I, EDWARD M. HEYLMAN, a citizen of the United States, and a resident of South Bend, in the county of St. Joseph and State of Indiana, have invented certain new and useful Improvements in Plows; and I do hereby declare the following to be a full, clear, and exact description of the invention, such as will enable others skilled in the art to which it appertains to make and use the same.

This invention relates to improvements in plows and more particularly to lifting means for the same,—one object of the invention being to provide simple and efficient means coöperable with the mounting of the rear furrow wheel and operable by power from another wheel of the plow and located at the rear end of the plow beam or frame to control the raising and lowering of the soil-engaging devices.

A further object is to provide simple and efficient means in power lift mechanism for locking parts of such mechanism in such manner that the plow will be locked either in a raised position, or locked down to its working position whereby the weight of the wheels will be brought to bear on the plow bases when in a working position to keep them at work in hard ground at a uniform depth.

A further object is to improve the construction of power lift mechanism and enhance the efficiency of the same in various respects.

With this and other objects in view, the invention consists in certain novel features of construction and combinations of parts as hereinafter set forth and pointed out in the claims.

In the accompanying drawings; Figure 1 is a plan view of a plow embodying my improvements; Fig. 2 is a view in side elevation showing the positions of the parts associated with the rear furrow wheel when the plow is elevated; Fig. 3 is a similar view showing the positions of the same parts when the plow bases are in working position; Fig. 4 is a plan view of the pivoted bracket in which the rear wheel axle is mounted; Fig. 5 is a separate view of the bracket in which the rear wheel axle bracket is pivotally mounted; Fig. 6 is a view partly in section, showing the crank shaft of the

lifting mechanism and the mounting of said shaft; Fig. 7 is an enlarged detail showing the adjustable connection of the operating rod with the arm of the crank shaft, Fig. 8 is a view showing the connections between the operating bar and the front furrow wheel mounting for effecting the raising of the front end of the frame when the rear end is raised, and Figs. 9 and 10 are sectional views showing the clutch devices, gearing and locking means of the power lift mechanism.

The frame of the plow structure comprises a beam 1 and a forward cross bar 2, with which latter the beam 1 is connected by means of a bracket or connector 3. The beam has secured thereto a plurality of brackets or standards 4 on which soil-engaging devices 5 are mounted. In the drawing I have illustrated the soil-engaging devices in the form of disks but it is evident that plow bases of the mold-board and share type might be employed.

The front cross bar 2 of the frame may be made angular in cross-section and it is tubular to form a bearing for a transverse shaft 6. A bracket 7 is secured to the angular cross bar 2 and is made with an upright tubular portion 8 which forms a bearing for the standard portion 9 of the axle of a front furrow wheel 10. A segment bracket 11 is mounted upon the upper end of the standard axle 9. A hand lever 12 is pivoted to the segment bracket 11 and is provided with a suitable detent to engage the segment, and a bar or pitman 13 connects said lever with a crank 14 at one end of the shaft 6, so that when said shaft is locked against turning (as hereinafter explained) and the hand lever 12 is operated, the forward portion of the frame may be raised or lowered.

A frame 15 is securely bolted to the rear end of the beam 1 and is made with tubular portions 16, 17 which provide bearings, respectively, for a crank shaft 18 and the axle 19 of a land wheel 20. The axle 19 is formed with a crank 21 on which the hub of the land wheel is mounted and said hub is provided with a sprocket wheel 22 from which motion is transmitted by a drive chain 23 to a sprocket wheel 24 mounted on the axle 19. The axle 19 also carries a pinion 25 which transmits motion to a gear 26 on

the crank shaft 18. Clutch mechanism 25^a is located between the pinion 25^b and the sprocket wheel 24, and controlled by a cord 26^a connected with a trip lever 27.

5 The rear end of the plow structure is supported at the furrow side thereof, by a rear furrow wheel 28, and the manner of mounting this wheel and operating it to provide rear wheel lifting means for the plow will 10 now be explained.

A bracket 29 is securely bolted to the rear standard bracket 4 of the plow frame and projects rearwardly therefrom. The bracket 29 is provided with rearwardly projecting lugs or ears 30 spaced apart for the accommodation of an axle bracket 31, the latter being pivotally connected with said lugs or ears by a suitable pin 32 and said bracket 31 is formed with a tubular portion 15 which receives the upper part of the axle 33 of the rear furrow wheel 28. The axle bracket 31 is made with a flanged arm 31^a which receives the inclined portion of the standard axle 33 and permits a limited pivotal movement of said axle. The bracket 29 is made with a transverse tubular portion 34 which constitutes a bearing for a shaft 35. This shaft is provided at one end with a crank arm 36, with which the upper end of a link 37 is pivotally connected, the lower 20 end of said link being pivotally attached to an arm 38 projecting forwardly from the lower portion of the axle bracket 31. To the other end of the shaft 35, an arm 39 is secured and projects upwardly therefrom. The arm 39 is provided at or near its upper end with a transverse hole in which the shank 40 of an internally threaded sleeve 41 is loosely mounted, said sleeve being disposed at right angles to the shank 40. These devices afford an adjustable and pivotal connection of a rod 42 with the arm 39, said rod having a threaded portion passing 25 through the sleeve 41. The other end of the rod 42 is pivotally connected with an actuating bar 43, the rear end of which latter is connected with the crank of the shaft 18 of the power mechanism. Several holes 42^a may be provided in the actuating bar 43 whereby the rod 42 may be adjustably attached thereto, so that the rear disk arms 30 can be adjusted on the main beam for changing the width of cut of each disk from 8, 9 and 10 inches. The sleeve 41 can be adjusted on the threaded portions of rod 42 to allow for the adjusting of a screw 45 in an arm 44 on the bracket 31. Any movement of the rear furrow wheel up or down when the plow is in working position will be prevented, it being desirable that the weight of the rear wheel shall be always on the disks or plow bodies.

The arm 44 which projects forwardly from the axle bracket 31 over the bracket 29 65 and carries at or near its free end, the ad-

justing screw 45 adapted to engage a seat 46 on said bracket 29, said screw being held in the position to which it may be adjusted by means of a jam nut 47. By means of this screw the rear furrow wheel 28 may be so 70 adjusted that its lower peripheral edge shall align with the lower cutting edges of the disks or plow bodies.

The forward end of the bar 43 is secured to a segment bracket 48 and the latter is supported by an arm 49, the upper end of said link being bifurcated and pivotally attached to the segment bracket 48 by means of a pin 50 and its lower end is adjustably secured to the shaft 6. A hand lever 51 is mounted on the pivot pin 50 and carries a suitable detent to engage the segment of the segment bracket 48. An arm 52 is rigidly secured to the hand lever 51 and to this arm, one end of a rod 53 is connected, the other end of 80 said rod being attached to an arm 54 secured to the land wheel axle 19. A balance spring 55 is connected with the arm 54 and with the lower depending portion 56 of the arm 49. By means of the lever 51, the crank axle 19 90 of the land wheel may be operated to effect leveling of the rear end of the plow structure, while the front portion of the latter may be leveled by manipulation of the lever 12. 95

When it is desired to raise the plow, the operator will manipulate the cord 26^a to throw the power mechanism into action, so that motion shall be transmitted from the hub of the land wheel 2 to the crank shaft 18. The turning of this crank shaft will cause the actuating bar 43 to move forwardly and this will cause a forward movement of the rod 42 and motion to be imparted, through the arm 39 to the crank 105 shaft 35. As the latter shaft turns, motion will be imparted by the link 37 to the arm 38 of the axle bracket 31, thus causing the latter to be moved from the position shown in Fig. 3 to the position shown in Fig. 2 and 100 the plow structure to be raised on the rear furrow wheel 28.

When the actuating bar 43 is moved forwardly as above described, the supporting link 49, with which the forward end of said bar is connected (through the medium of the segment bracket 48) will be moved forwardly, thus causing the crank shaft 6 to turn and impart a lifting action to the forward end of the plow frame, through the 115 medium of the connections between said crank shaft 6 and the standard axle 9 of the front furrow wheel 10.

The forward movement of the actuating bar 43 and arm 49, will also cause a forward movement of the segment bracket 48 and the hand lever 51 which is locked to the segment by its detent. As the lever thus moves forwardly, motion will be imparted, through the arm 52 and rod 53 to the arm 54 on the 125 130

crank axle 19, thus causing the latter to be turned and the landside side of the plow structure raised.

The ratio of the gears 25 and 26 is such that a complete rotation of the smaller gear 25 which is connected with the clutch devices, will cause a one-half rotation of the larger gear 26 and consequently a one-half rotation of the crank shaft 18. It will be observed that the actuating bar 43 will normally bear a dead-center relation to the axis of the crank shaft 18 and the forward connection of the actuating bar, when the plow is in working position, as shown in Figs. 1 and 3, and that when the shaft 18 shall have been turned a one-half rotation during the lifting operation, the actuating bar will have again assumed a dead center relation to the axis of the crank shaft 18 as shown in Fig. 2 and it will thus be seen that a dead-center lock is provided for the plow when the latter is in either its working or in its raised position. In order that the gearing shall be held in position at each half rotation of the shaft 18 and thus insure the maintenance of the dead-center relation of the actuating bar to the axis of the shaft 18 when the plow is in either working or raised position, a locking lever 57 is provided. This lever is pivoted at 58 and is provided with a V-shaped or cam notch 59 for engagement with one or another of two pins 60 (having rollers 61 thereon) located at diametrically opposite points on the gear 26, proper engagement of the locking lever with one or the other of said pins being insured by the action of a spring 62. This spring is attached at one end to the locking lever and its other end may be attached to the trip lever 27.

It is apparent that when it is desired to lower the plow, the trip lever 27 may be operated to cause the gear 26 to overcome the locking means and permit the plow to descend to and become locked in working position.

Various slight changes might be made in the details of construction of my invention without departing from the spirit thereof or limiting its scope and hence I do not wish to restrict myself to the precise details herein set forth.

Having fully described my invention what I claim as new and desire to secure by Letters-Patent, is:—

1. In a plow structure, the combination with a wheeled frame and a plow, of lifting means including a crank shaft and an actuated bar connected therewith and normally bearing dead-center relations to each other, a gear on said crank shaft, power operated means for imparting half-rotations to said gear, and means coöoperating with said gear to hold the same at the end of each half rotation when the actuating bar

bears a dead center relation to the crank shaft, whereby the plow will be held either in a raised position or a working position.

2. The combination with a plow frame, a forward furrow wheel, raising means movably connecting the frame with the axle of said wheel, a land wheel, a crank axle for the latter mounted at the rear end portion of the frame, an axle bracket pivotally connected with the rear end of the frame, a rear furrow wheel, and an axle for the latter having a part mounted in said pivoted axle bracket, of power mechanism on the rear portion of the frame, driving means for said power mechanism connected with the land wheel, an actuating bar connected with said power mechanism, connections between said actuating bar and the rear axle bracket for raising the rear end of the frame, connections between said actuating bar and the raising means associated with the front furrow wheel, and connections between said last-mentioned connections and the crank axle of the land wheel for turning said crank axle when the actuating bar is moved.

3. The combination with a plow frame, a forward furrow wheel, an axle therefor, a rear furrow wheel, an axle therefor, a bracket pivotally connected with the rear end of the frame and affording a bearing for the axle of the rear furrow wheel, a crank axle mounted at the rear end of the frame, and a land wheel having its hub mounted on said crank axle, of power mechanism mounted at the rear end of the frame, driving means between said power mechanism and the hub of the land wheel, and lifting connections between said power mechanism and the axles of the front furrow wheel and the land wheel, and operating means connecting said lifting connections with the pivoted axle bracket of the rear furrow wheel axle.

4. The combination with a plow frame, a front furrow wheel, a standard axle therefor, a crank shaft mounted at the forward end of the frame, a land wheel, a crank axle therefor mounted at the rear portion of the frame, an axle bracket pivotally connected with the rear end of the frame, a rear furrow wheel, and an axle therefor having a part mounted in said axle bracket, of power mechanism at the rear portion of the frame and operatively associated with the land wheel, said power mechanism including a crank shaft, an actuating bar connecting said last-mentioned crank shaft with the forward crank shaft, connections between said actuating bar and the land-wheel crank axle, and connections between said actuating bar and the pivoted axle-bracket of the rear furrow wheel axle.

5. The combination with a plow frame, a front furrow wheel, a standard axle therefor, a land wheel, a crank axle therefor, an

- axle bracket pivotally connected with the rear portion of the frame, a rear furrow wheel, an axle for the latter having a part mounted in said pivoted axle bracket, and 5 power mechanism operatively associated with the land wheel and including a crank shaft, of a crank shaft at the forward end of the frame, connections between said forward crank shaft and said standard axle, an arm 10 secured to said forward crank shaft, an actuating bar pivotally connected at its forward end with said arm and attached at its rear end to the crank shaft of the power mechanism, a lever supported by said arm, means 15 for locking said lever, and a connection between said lever and the land wheel crank axle.
6. The combination with a plow frame and wheel operated power mechanism, of an axle 20 bracket pivotally connected with the rear end of said frame, a crank shaft supported by the frame, a link connected at one end with the crank of said shaft and at the other end to the pivoted axle bracket, an arm 25 on said crank shaft, and connections between said arm and the power mechanism.
7. The combination with a plow frame, wheel operated power mechanism including a crank shaft, and an actuating bar connected with said crank shaft, of an axle 30 bracket pivotally connected with the rear end of the frame and having a forwardly projecting arm, a rear furrow wheel, an axle therefor having a part mounted in said axle 35 bracket, a crank shaft supported by the frame, a link connecting the crank of said shaft with the arm of the axle bracket, an arm on said crank shaft, and a rod connecting 40 said arm with the actuating bar.
8. The combination with a plow frame, soil-engaging devices carried thereby, wheel 45 operated power mechanism including a crank shaft, and an actuating bar connected with said crank shaft, of an axle bracket pivotally connected with the frame and having upper and lower forwardly projecting arms, a rear furrow wheel, an axle therefor 50 having a part mounted in said axle bracket, a crank shaft supported by the frame, a link connecting said crank shaft with the lower arm of said axle bracket, an adjusting screw
- passing through the upper arm of the axle bracket and adapted to engage a part on the frame to adjust the rear furrow wheel relatively to the soil-engaging devices, an arm on 55 said last-mentioned crank shaft, and a rod connecting said arm with the actuating bar.
9. The combination with a plow frame, and a pivoted axle bracket at the rear end thereof, said axle bracket having an arm, a rear furrow wheel, and an axle for said wheel having a part mounted in said pivoted axle bracket, of a crank shaft supported by the frame, a link connecting the crank of said shaft with the arm of said axle bracket, an 60 arm on said crank shaft, a sleeve having a pivotal mounting in said arm, an operating rod having a threaded part passing through said sleeve, and means for operating said operating rod.
10. The combination with a plow frame, of a fixed bracket at the rear end thereof and having a transverse tubular portion, an axle bracket pivoted to said fixed bracket and having an arm, a rear furrow wheel, an axle 70 therefor having a part mounted in said axle bracket, a crank shaft mounted in the tubular portion of the fixed bracket, a link connecting the crank of said shaft with the arm of the axle bracket, an arm on said crank 75 shaft, and operating means connected with said arm.
11. The combination with a plow frame, an axle bracket pivotally connected with the rear end thereof, a rear furrow-wheel, and an axle therefor having a part mounted in said axle 80 bracket, of a crank shaft supported by the frame and connected with said axle bracket, an arm on said crank shaft, an actuating bar, wheel-operated power means, connections between said power means and said actuating bar, and an operating rod connected at one end with said arm on the crank shaft and adjustably connected at its other 85 with said actuating bar.
- In testimony whereof, I have signed this specification in the presence of two subscribing witnesses.
- EDWARD M. HEYLMAN.
- Witnesses:
- EDWIN VICAR,
CHAS. A. WEBSTER.
